Primary Examiner — Jennifer L Watkins*Assistant Examiner* — Bryan Coauhemic Gusman(57) **CLAIM**

The ornamental design for a pillow, as shown and described.

DESCRIPTION

FIG. 1 is a front, right side, bottom perspective view of a pillow showing my new design;

FIG. 2 is a rear, right side, top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a rear, right side, top perspective view thereof with a central portion of the rear section of the pillow removed from the pillow.

The broken depict portions of the pillow that form no part of the claimed design.

1 Claim, 9 Drawing Sheets(56)
